UNITED STATES PATENT OFFICE.

THEODORE W. GABEL, OF LANCASTER, PENNSYLVANIA.

ELECTRIC SWITCH.

SPECIFICATION forming part of Letters Patent No. 556,264, dated March 10, 1896.

Application filed May 13, 1895. Serial No. 549,090. (No model.)

To all whom it may concern:

Be it known that I, THEODORE W. GABEL, a citizen of the United States, residing at Lancaster, in the county of Lancaster and State 5 of Pennsylvania, have invented certain Improvements in Electric Switches, of which the following is a specification.

This invention relates to improvements in devices designed for making and breaking an 10 electric current and changing the course of the same, and is particularly applicable to that class of dental instruments employed in operating on the teeth of the patient; and the objects of the invention are, first, to cut out 15 the instrument used on the patient, so that the stoppage of the action of said instrument shall be instantaneous; second, to regulate the strength of the current applied, and, third, to reverse said current.

20 The invention consists in the construction and combination of the various parts, as hereinafter fully described and then pointed out in the claims.

In the accompanying drawings, which form 25 a part of this specification, Figure 1 is a top view of a foot-rest containing the mechanism embodying my invention, and Fig. 2 a longitudinal vertical section thereof. Fig. 3 is a horizontal section on broken line 3 3 of Fig. 30 2, showing a top view of the plate supporting the operating mechanism, and Fig. 4 a similar section on broken line 4 4 of Fig. 2, showing a bottom view of said plate. Fig. 5 is a vertical section on broken line 5 5 of Fig. 4; 35 Fig. 6, a vertical section on broken line 6 6 of Fig. 3, and Fig. 7 a similar section on broken line 7 7 of Fig. 3.

Similar letters indicate like parts throughout the several views.

40 For the purposes of this specification the wires connecting the mechanism herein described with the source of electricity are termed "line-wires."

Referring to the details of the drawings, A 45 indicates the tread of a hollow foot-rest, having in the toe thereof a curved slot a and in the heel a straight slot a' .

A' indicates a horizontal plate to which is attached the mechanism comprising my invention.

B and B' are line-wires, D an insulating case located on plate A' and containing a re-

sistance-coil D' , and E a horizontally-movable switch-lever pivoted to the bottom of said plate A' at e . This lever is formed of 55 spring metal and has a post E' on its forward end extending up through plate A' and the slot a , and is provided with a head or annular rim e' . The rear end e^2 of lever E is adapted to be engaged with any one of a number of binding-posts d d' d'' , &c., disposed concentrically with the pivot of lever E and passing up through plate A' .

F' are switch-bars pivotally connected by a non-conducting plate F^2 and pivoted above 65 plate A' on binding-posts f f' , respectively, their free ends being adapted to engage the binding-posts G G' and G^2 , passing through said plate A' . On plate F^2 is pivoted a post F^3 , which extends up through slot a' and is 70 adapted to be actuated sidewise by the heel of the foot.

The line-wires pass into the foot-rest above plate A' through an opening a^2 . Line-wire B is then carried down through a perforation b in said plate and, as shown at b' , over to the pivot e of lever E. Line-wire B' is also carried down through a perforation b^2 , and, as shown at b^3 , over to binding-post f' , the pivot of switch-bar F' . 75

The wires H H' , connected with the dental instrument, also pass into the foot-rest through opening a^2 , the wire H being carried down through perforation h , and thence to binding-post G , as shown at h' , and wire H' down 80 through perforation h^2 , and thence to binding-post G' , as shown at h^3 .

Below the bottom of plate A' binding-posts G' and G^2 are connected by a wire g , and the upper end of binding-post d is connected with 90 the bottom of binding-post f —the pivot of switch-bar F —by a wire g' passing through perforation g^2 .

Binding-post d is connected with a terminal d^2 of resistance-coil D' , while binding-posts d' to d^4 , inclusive, are connected therewith by branch wires d^8 , the coil finally terminating at the binding-post d^5 , the binding-post d^6 having no connection with the coil, whereby, as the end e^2 of lever E successively 95 engages the lower ends of said binding-posts, the resistance to the flow of the current is proportionably increased, as is usual in constructions for regulating the strength of an 100

electric current, until said switch reaches binding-post d^6 . When end e^2 of said lever E is engaged with the lower end of binding-post d the current passes directly from said post to binding-post f —that is to say, without passing through any portion of resistance-coil D'. If, however, the lever E is turned so as to make connection with binding-post d' , the current before reaching binding-post d must first pass through that portion of the resistance-coil which is interposed between binding-posts d and d' . Hence the strength of the current will be diminished accordingly, and in like manner if the lever E is moved into contact with the binding-post d^2 the current will have to pass through a greater extent of the resistance-coil and there will be a further diminution of the strength of the current, and so on until lever 15 E makes connection with the binding-post d^5 , whereby the entire extent of the resistance-coil is introduced into the circuit and the power of the current is reduced to a minimum, further movement of the lever E into 20 contact with the binding-post d^6 cutting off the current and switching the dental instrument out of the circuit. In like manner the power of the current is gradually increased as the lever E swings from the binding-post 25 d^5 to the binding-post d .

No particular construction or arrangement of resistance-coil is shown or described, as the same does not form any part of this invention, and any kind of rheostat through 30 which the strength of the electric current can be regulated may be employed.

Switch-lever E is swung to and fro about its pivot by the side pressure of the toe of the foot on post E'. Said lever being in contact 35 with binding-post d and the switch-bars F and F' contacting, respectively, with binding-posts G' and G, as shown by broken lines R, the current is through line-wire B b', pivot e and lever E, binding-post d and wire g' , binding-post f , switch-bar F, binding-post G' and instrument-wire h^3 II', returning through instrument-wire II' h' , binding-post G, switch-bar F', binding-post f' and line-wire b^3 B'. To reverse the current, switch-bars F and F' 40 are thrown into contact with binding-posts G and G^2 , respectively, as shown by broken lines R. The current is then through line-wire B b', pivot e and lever E, binding-post d and wire g' , binding-post f , lever F, binding-post G and instrument-wire h' II, returning through instrument-wire II' h^3 , binding-post G' , wire g and binding-post G^2 , lever F', binding-post f' and line-wire b^3 B'; but it is often 45 desirable to cut out the operating mechanism, so that the movement of the instrument may be stopped instantaneously. Beneath plate A', and just back of slot a, is located a bracket or bridge M of conducting material, which 50 electrically connects with line-wire B' outside of the connection of said line-wire with the switch-bars by a branch wire m , passing

through a perforation m' in plate A' and a binding-screw m^2 . By pressing on head e' of post E' lever E is engaged with bridge M, as 55 illustrated by broken lines at M', Figs. 2 and 5. The circuit is then through line-wire B b', pivot e and the front end of lever E, bridge M, binding-screw m^2 , wire m and line-wire B'.

I do not restrict myself to cutting out the 75 operating-instrument by means of the short circuit described, nor by means of any construction of short circuit; neither do I limit myself to the other details of construction herein shown and described, as it is obvious 80 that many changes may be made therein without departing from the scope and principle of my invention.

Having thus described my invention, what I claim as new, and desire to secure by Letters 85 Patent, is—

1. The combination, in an electric switch, of a resistance-coil, a series of contacts, each of said contacts having a different point of connection with the resistance-coil, a conductor-switch formed of a plain lever-bar, an end of said lever-bar having a terminal adapted to engage each of said contacts, a line-wire connected with the fulcrum of the lever-bar, a pair of pivoted conductor switch-bars connected by a non-conducting plate, three contacts located within the path of travel of the swinging ends of the connected switch-bars, a second line-wire connected with the pivot of one of the connected switch-bars, 100 a conductor connecting the pivot of the other of said connected switch-bars and one of the terminal contacts of the resistance-coil, a connection between the end contacts of said three contacts, a connection between one of 105 said end contacts and the actuated mechanism, and a connection between the center contact of the three contacts and said actuated mechanism, substantially as and for the purpose specified. 110

2. The combination, in an electric switch, of a resistance-coil, a series of contacts, each of said contacts having a different point of connection with the resistance-coil, a conductor-switch formed of a plain lever-bar, one 115 end of said bar having a terminal adapted to engage each of said contacts, the other end of said lever-bar being formed of spring material and adapted to be depressed, a conductor-bridge located beneath said lever-bar in position to be engaged by the spring end of said bar when depressed, a line-wire connected with the fulcrum of the lever-bar, a pair of pivoted conductor switch-bars connected by a non-conducting plate, three contacts located 120 within the path of travel of the swinging ends of the connected switch-bars, a second line-wire connected with the pivot of one of the connected switch-bars, a conductor connecting the pivot of the other of said connected 125 switch-bars and one of the terminal contacts of the resistance-coil, a connection between the end contacts of said three contacts, a connection between one of said end contacts and

the actuated mechanism, a connection between the center contact of said three contacts and said actuated mechanism, and a direct connection between said bridge and the line-wire connected with said pivot of one of the connected switch-bars, substantially as and for the purpose specified.

3. The combination, in an electric switch, of a hollow foot-rest having a slot in each end thereof, a switch mechanism located in said foot-rest and comprising a resistance-coil, a series of contacts, each of said contacts having a different point of connection with the resistance-coil, a conductor-switch formed of a plain lever-bar, one end of said lever-bar being adapted to engage each of said contacts, the other end of said lever-bar being formed of spring material and adapted to be depressed, a conductor-bridge located beneath said bridge in position to be engaged by the spring end of the lever-bar when depressed, a post on said end of the lever-bar passing up through one of the slots in the foot-rest, a pair of pivoted conductor switch-bars connected by a non-conducting plate, a

post on said plate extending up through the other slot in the foot-rest, three contacts located within the path of travel of the swinging ends of the connected switch-bars, a connection between the end contacts of said three contacts, and a conductor connecting the pivot of one of said connected switch-bars and one of the terminal contacts of the resistance-coil, with a line-wire attached to the pivot of the other of said connected switch-bars, another line-wire attached to the fulcrum of the lever-bar, a connection between said bridge and the line-wire connected with the pivot of one of said connected switch-bars, a connection between one of the end contacts of said three contacts and the actuated mechanism, and a connection between the center contact of said three contacts and the actuated mechanism, all substantially as and for the purpose specified.
